UNITED STATES PATENT OFFICE.

WILLIAM J. WARREN, OF CARDSTON, ALBERTA, CANADA.

WIRE CUTTER.

1,414,239.

Specification of Letters Patent. Patented Apr. 25, 1922.

Application filed July 12, 1918. Serial No. 244,588.

To all whom it may concern:

Be it known that I, WILLIAM J. WARREN, a subject of the King of Great Britain, residing at Cardston, in the Province of Alberta 5 and Dominion of Canada, have invented certain new and useful Improvements in Wire Cutters; and I do hereby declare the following to be a full, clear, and exact description of the invention, such as will enable others 10 skilled in the art to which it appertains to make and use the same.

My invention relates to improvements in wire cutters especially adapted for cutting wire entanglements in warfare.

15 An important object of my invention is to provide a wire cutter of the character described which is disposed forwardly of an armored motor car, tank or other vehicle used in warfare.

20 A further object of the invention is to provide a device of the character described which may be applied to an armored motor car, and so forth, in a highly expeditious manner and with but slight variation in the structure of 25 the vehicle.

A further object of the invention is to provide a wire cutting implement adapted for attachment to an armored motor car or tank, which is positive in its operation and re-

30 quired no attention from the operator of the vehicle.

Other objects and advantages of the invention will be apparent in the course of the following description.

35 In the accompanying drawings forming a part of this specification and in which like numerals are employed to designate like parts throughout the same,

Figure 1 is a side elevation of my improved 40 wire cutting implement,

Figure 2 is a side elevation of a cutting blade of my improved wire cutting device,

Figure 3 is a central vertical sectional view through my improved wire cutter, and,

45 Figure 4 is a plan view of my improved wire cutting device attached to a source of power.

In the drawings, wherein for the purpose 50 of illustration is shown the preferred embodiment of my invention, the numeral 5 designates a rotary blade corresponding in structure to a coacting rotary blade 6. The blades 5 and 6 are mounted on a stationary shaft 7 and are adapted to partake of rotary 55 movements in opposite directions. The shaft

7 is journaled through the forward end of a bracket 8 attached to the front of a tank or armored motor car 9 as at 10. A power shaft 11, extending from the motor of the tank or armored motor car, carries a sprocket 12 60 driving a sprocket chain 13 arranged on a sprocket gear 14 carried by the blade 5. Keyed to the shaft 11 and inwardly of the sprocket gear 12 is a gear 15 meshing with a second gear 16. The gear 16 is mounted on a 65 stub shaft 17 which carries a sprocket gear 18. The rotary blade 6 carries a sprocket gear 18' engaging a second sprocket chain 19 extending to the sprocket gear 18. By this particular arrangement of gearing, it is ob- 70 vious that the blades 5 and 6 are rotated in opposite directions as indicated by the arrows. The rotary blades 5 and 6 carry a series of arcuate shaped members 20 having cutting edges 21 extending radially of the 75 shaft 7. It is apparent that the wire upon coming between the blades 21 will be severed by the positive rotation of the blades 5 and 6.

The cutting edges of each blade are straight and are arranged radially whereby 80 the cutting edges of one blade will be substantially parallel with the cutting edges of the other blade upon engaging and severing a wire.

In the operation of my device, it is appar- 85 ent that the rotary blades 5 and 6 are rotated in opposite directions as hereinbefore described and are mounted forwardly of a tank or motor car and upon coming in engagement with wire entanglements, the cut- 90 ting action of the blades 21 severs the wire.

While I have shown specific means for causing the blades 5 and 6 to partake of rotary movement in opposite directions, it is obvious that any suitable means may be em- 95 ployed to accomplish this end and it is understood that I may make such minor changes in arrangement and construction of parts as will remain within the spirit of the invention and the appended claim.

Having thus described my invention, what I claim is:

A wire cutting mechanism comprising a fixed shaft, a bracket mounting said shaft, an abutment on said shaft, cooperating cutters 105 in contact journaled on said shaft one abutting said bracket and the other abutting said abutment, said cutters being substantially vertically disposed and having radial cutting teeth, sprocket wheels associated with said 110

cutters, chains trained over said sprocket wheels, second sprocket wheels over which said chains are trained, shafts for said second sprocket wheels, one of said shafts for the 5 second sprocket wheels being a drive shaft, and means to drive the shaft for the other sprocket wheel from said drive shaft whereby

the cutters are moved in opposite directions.

In testimony whereof I affix my signature in presence of two witnesses.

WILLIAM J. WARREN.

Witnesses:

GORDON DICK HAMILTON,
WILLIAM SMITH JOHNSTON.
